DESIGN FOR A CARPENTER'S PLANE

Rene Gouirand, New York, N. Y.

Application January 21, 1947, Serial No. 136,270

Term of patent 3½ years

(Cl. D93—4)

To all whom it may concern:

Be it known that I, Rene Gouirand, a citizen of the United States of America, residing at New York, in the county and State of New York, have invented a new, original, and ornamental Design for a Carpenter's Plane, or which the following is a specification, reference being had to the accompanying drawing, forming part thereof.

Fig. 1 is a perspective view showing a carpenter's plane of my new design.

Fig. 2 is a side elevation thereof.

Both sides of the plane are the same and the bottom of the plane is flat.

I claim:

The ornamental design for a carpenter's plane, as shown and described.

RENE GOUIRAND.
